UNITED STATES PATENT OFFICE.

JOSEPH SIGMUND, OF DENVER, COLORADO.

DISPLAY-STAND.

1,125,194.

Specification of Letters Patent.

Patented Jan. 19, 1915.

Application filed August 20, 1913. Serial No. 785,777.

To all whom it may concern:

Be it known that I, JOSEPH SIGMUND, a citizen of the United States, residing at Denver, in the county of Denver and State of Colorado, have invented certain new and useful Improvements in Display-Stands, of which the following is a specification.

This invention relates to display stands for use in stores, show windows and other places where it is desired to exhibit articles of merchandise to good advantage.

The principal object of my invention resides in the provision of a collapsible structure the parts of which when not in use, 15 may be folded within a small compass, and when employed for the purpose for which the structure is designed, will present a strong, rigid and ornamental stand upon which a large number of objects may be 20 attractively displayed in a comparatively small space.

With this and other objects in view my invention consists in the peculiar construction and arrangement of parts shown in 25 the accompanying drawings, in the several views of which like parts are similarly designated, and in which,

Figure 1 represents a perspective view of my improved display stand in its condition 30 ready for use, Fig. 2, a similar view of the supporting structure of the stand, Fig. 3, a perspective view of the stepped top of the stand in a partly folded condition, Fig. 4, a perspective view of one of the side pieces 35 of the supporting structure in the folded condition, Fig. 5, a transverse section through the stand shown in Fig. 1, drawn to an enlarged scale, Fig. 6, a sectional view of one of the fastenings by means of which 40 the connecting bars of the supporting structure are attached to the side pieces of the same, Fig. 7, a side elevation of a stand composed of two units which conjointly provide a continuous series of stepped 45 shelves, and Fig. 8, a plan view of a number of units arranged in co-operative relation to present a stand of angular form.

Referring more specifically to the drawings, the reference numeral 2 designates the 50 supporting structure of the stand which as best shown in Fig. 2, consists of two upright, right-angled, triangular side frames 3 which are rigidly connected in parallel relation to each other by a plurality of 55 bars 4.

Each of the frames consists of two right

angularly disposed members 5 and 6 which at their adjoining ends are detachably united by means of a latch hook and staple, as shown at 7 in Figs. 2 and 5, while at 60 their opposite ends they are connected by means of hinges 8 to a hypotenusal member 9 which at its upper edge is stepped for the support of the top of the stand hereinafter to be described.

The joints of the members 5, 6 and 9 of the frame 3 are arranged so that they may be folded upon each other in parallel relation as shown in Fig. 4, to form a compact article which may be readily carried, or 70 stored in a small space when not in use.

The bars 4 which connect the side pieces 3 to provide in conjunction therewith, a strong and rigid structure for the support of the shelves and the objects displayed 75 thereon, are provided at their extremities with angularly disposed, preferably metallic tenons 10 which are adapted to enter correspondingly formed sockets provided by U-straps 12 which are secured by nails 80 or screws at the inner surfaces of the uprights 3.

The folding top of my improved stand consists of a series of steps formed of a plurality of oblong members 14 and 15 which 85 are connected at their adjoining longitudinal edges by means of hinges 13. The articulately connected members of the top provide when the members are in place upon the supporting structure, a series of 90 alternate shelves and risers which engage the corresponding edges of the steps cut in the oblique members 9 of the uprights 3.

The risers 15 are provided with panels 16 which are hinged at their lower edges in 95 openings 17 in which they are removably fitted, and which at their inner sides are provided with knobs 24 to facilitate their being moved about their hinges for the purpose of affording access from the inside of 100 the structure to objects disposed on the shelves.

The hinges 13 which connect the several members of the top are arranged alternately at opposite sides of their adjoining edges 105 so that when the stand is not in use the top may be folded into an article whose dimensions equal the length and width of one of its members and the combined thickness of all of them.

While for clearness of illustration the hinges which connect the members of the

top and those of the side frames have been shown exposed in the drawings, they are in reality concealed by coverings of cloth with which the outer surfaces of the parts of the 5 stand are provided to give to the structure the artistic and ornamental appearance required for the purposes for which it is principally used.

In Fig. 7 of the drawings a stand has 10 been shown which is composed of two units 18 and 19 which conjointly provide a continuous series of stepped shelves of double the number of those of the single stand hereinabove described. One of the units, 15 18, is identical in construction, form and dimensions to the structure shown in Fig. 1, but in the other unit, 19, the side pieces of the supporting structure have been elongated to elevate the top supported upon 20 their stepped edges to the height required for its continuity with the top of the other unit. This elongation of the side pieces is readily accomplished by inserting an additional upright member 20 between the lower 25 end of the oblique member 9 and the corresponding end of the lower horizontal member 5, and by proportionately lengthening the third, upright member 6.

To enable the side pieces of the modified 30 supporting structure to be folded like those of the ordinary structure, the additional members 20 thereof are connected at their ends to the adjoining members 5 and 9 by means of hinges 21, and the lengthened 35 members 6 are composed of two hinged sections which may be locked in their alined position by means of sliding bolts 22.

In Fig. 8 of the drawings is shown an arrangement of units 23 which are placed 40 adjoining in angular relation to each other and which vary from those hereinbefore described only in the form of their tops which for the purposes of their continuity with those of adjoining units are composed of 45 trapeziform shelves and risers of gradually decreasing lengths.

It will be understood that by methods 50 such as are illustrated in Figs. 7 and 8, the units may be arranged so as to form display stands of various forms and proportions, the parts of which are readily assembled and put in their proper relative position, and when not in use can be folded within a small compass to occupy a portable box, if 55 so desired.

While I have shown and described my dis-

play stand in the best form at present known to me, I desire it understood that variations in the form, proportion and arrangement of its parts may be resorted to within the 60 spirit of my invention as defined in the following claims.

1. A display stand comprising a supporting structure composed of detachably connected, folding, upright side pieces each 65 made of three members which are connected by hinges at their adjoining ends, corresponding members of said pieces having correspondingly stepped edges, and a folding top supported on the steps of the said 70 members.

2. A display stand comprising a supporting structure composed of detachably connected, right-angled triangular side pieces 75 which are each composed of three members two of which are connected to the third member by hinges, and to each other by means of a detachable fastening, the said third members of the said pieces having correspondingly stepped edges, and a folding top supported on the steps of said members.

3. A display-stand comprising a supporting structure having stepped edges, and upon the steps of the same, a folding top 85 composed of shelves for the support of merchandise, and risers connected along their opposite longitudinal edges, with the shelves by means of hinges and extending rearward of the said supporting surfaces of 90 the same, the said risers having openings affording access to the said surfaces of the shelves with which they are connected at their lower edges, and inwardly moving panels for closing said openings. 95

4. A display stand comprising a pair of units each including a collapsible supporting structure and a folding top which is stepped to provide a series of shelves, the supporting structure of one of said units 100 being constructed to support the respective top at an elevation above that at which the top of the other unit is supported, whereby the two tops provide conjointly, a continuous series of shelves when the said units 105 are placed adjoining each other.

In testimony whereof I have affixed my signature in presence of two witnesses.

JOSEPH SIGMUND.
